UNITED STATES PATENT OFFICE.

DANIEL PYZEL, OF PIEDMONT, CALIFORNIA, ASSIGNOR TO SIMPLEX REFINING COMPANY, OF SAN FRANCISCO, CALIFORNIA, A CORPORATION OF CALIFORNIA.

APPARATUS FOR REFINING OILS.

Application filed October 26, 1921. Serial No. 510,561.

To all whom it may concern:

Be it known that I, DANIEL PYZEL, a subject of the Queen of the Netherlands, residing at Piedmont, in the county of Alameda and State of California, have invented a new and useful Apparatus for Refining Oils, of which the following is a specification.

My invention relates particularly to the refining of petroleum oils.

The principal object of my invention is to produce a refining system in which a certain desired product may be obtained by means which may be easily controlled by the operator.

While my invention is applicable to any refining system, it is particularly applicable to so called cracking systems, in which the oil to be refined is subjected to heat or pressure, or both, for the purpose of changing its physical characteristics or molecular structure.

By the use of my invention, the efficiency of such cracking systems can be largely increased and the desired product can be obtained with greater certainty than is at present possible.

Further objects and advantages will be made evident hereinafter.

Referring to the drawing which is for illustrative purposes only,

Fig. 1 is a sectional elevation through one embodiment of an apparatus suited to carry on my invention.

Fig. 2 is a plan view of same.

In the embodiment shown, 11 is a heater, 12 is a vapor separator, 13 is a dephlegmator, 14 is a cooler, 15 is a circulating pump, 16 is a condenser and 17 is a feed pump.

The heater 11 and the vapor separator 12 form a means for heating and removing vapor from oil, and are hereinafter sometimes referred to as a "still". Other well known forms of stills may be substituted for the parts 11 and 12 without departing from the spirit of my invention.

In the form shown, 21 is a pipe coil, situated in a furnace 22 having a chimney 23 and being heated by a gas or oil burner 24. Oil enters the coil 21 through a pipe 25 being delivered from the coil 21 through a pipe 26 into the top of the vapor separator 12.

The vapor separator 12 consists of a tight shell 30, having a series of spreader cones 31 therein. The heated oil which contains bubbles of vapor therein flows downwardly over

these cones and in a thin film over the inner walls of the shell 30, the vapor escaping therefrom during the downward passage of the oil. These vapors are withdrawn from the shell 30 through a pipe 31^a and are delivered to the bottom of the dephlegmator 13. The residuum, free from its vapor, passes through a pipe 33 controlled by a valve 34 to suitable storage.

The dephlegmator 13 consists of a tight shell 40 having a series of shallow pans 41 and 42 therein. The pans 41 are smaller in diameter than the interior of the dephlegmator, allowing vapor to pass upwardly and liquid to pass downwardly around the outer edge thereof. The pans 42 fit tightly inside the dephlegmator but have openings 43 in the center thereof through which vapors ascend and through which liquid may pass downwardly. The highly heated vapors from the pipe 31^a pass in a tortuous course through the pans 42 and around the pans 41 being finally withdrawn through a pipe 45 which delivers them to the top of the condenser 16.

The oil to be refined is delivered through a pipe 46 controlled by a valve 47 into the top of the dephlegmator 13, this oil filling the pans 41 and 42 and dropping downwardly through the space around the pans 41 and through the openings 43. The oil delivered through the pipe 46 is at atmospheric temperature. In its passage downwardly through the dephlegmator 13, it is in intimate contact with the vapor delivered from the still and several results are accomplished therein.

In the first place the oil is considerably heated by the vapors, thereby conserving a certain number of heat units which would otherwise have to be taken up in the condenser 16. There may also be in the oil a certain percentage of gasoline, benzine or other volatile hydrocarbons which readily distill off at comparatively low temperatures. The heating of oil causes these hydrocarbons to distill and to go off with the other vapors through the pipe 45 into the condenser 16, thus further conserving the heat units and further assisting in cooling the vapor. In any still the vapors taken off are a mixture of various hydrocarbons, the lighter ones being those usually desired and the heavier ones being those ordinarily of less value. In cracking hydrocarbons the main purpose is to change the heavier hydrocar-

bons into lighter ones. The heavier hydrocarbons are much more easily condensed than the lighter ones and the cooling action of the oil on the vapors in the dephlegmator 13 tends to condense these heavier hydrocarbons from the vapor, these condensates mixing with the crude oil and being carried downwardly therewith to the still where they are again subjected to the cracking process. At the same time lighter hydrocarbons which are more difficult to crack and, if reaching the still would interfere with the regular course of the cracking process, are distilled off in the dephlegmator 15 and in this way are prevented from reaching the still.

This mixture of condensates and crude oil freed from its lightest fractions at a considerably elevated temperature is delivered 20 through a pipe 48 and valves 49 to the pump 17 which in turn forces it through the pipe 25 back into the still. In the still distillation and cracking occurs, the vapors passing off through the pipe 31^a where they are again 25 acted upon.

I have found that while the supply of crude oil in ordinary distillation will, in some cases, be sufficient to accomplish the necessary cooling of the vapors, where cracking stills are operated the vapors are at such 30 a high temperature that the oil is not sufficient in quantity to effect the desired cooling, or what is the same thing, that certain fractions are distilled from the oil and pass over 35 through the vapor line 45 which it is desired to pass into the still.

For the purpose of assisting in the cooling, and more particularly for the purpose of allowing the operator to control the temperature of the vapor in the pipe 45, and the oil in the pipe 25, I provide the cooler 14. This cooler is of the type shown, consisting 40 of tubes 50, situated between heads 51 and 52 and cooled by water delivered and withdrawn through the pipes 53. A portion of 45 the fluid is taken from the pipe 48 through a pipe 54 to the suction side of the pump 15, being forced through a pipe 56 and through

the tubes 50 into a pipe 57 from which it is delivered to the top of the dephlegmator 13. 50 By providing a sufficiently large cooler 14, the operator is able to fully control the temperature in the dephlegmator 13 by varying the speed of the pump 15, or he may control this temperature by regulating the water 55 flowing through the pipes 53. In either case, in the event that the temperature of the vapor in the pipe 45 or the temperature of the oil in the pipe 25 becomes excessive, it is simply necessary to speed up the pump 15 or increase the flow of the cooling water through the pipes 53. The operator is thus able by very simple means to absolutely control these temperatures and to thus make an accurate division of the oil. All of the oil 60 which will distill at a temperature below the temperature of the dephlegmator will pass off as vapor through the pipe 45, and all of the vapor which will condense at that temperature will pass over as a liquid 70 through the pipe 25.

I claim as my invention:

In an oil refining system the combination of: a still; a tight shell; means for delivering the cold oil to be refined to the top of 75 said shell; means inside said shell for finely dividing and spreading the oil as it passes through said shell; means for passing the vapors from said still upwardly through said shell in intimate contact with the oil 80 passing downwardly through said shell so that it may condense and absorb a portion of said vapors; a cooler; means for withdrawing a portion of said oil and its associated condensates from said shell and delivering 85 it to said cooler; means for delivering said cooled oil and condensates into the top of said shell; and means for delivering oil and its associated condensates from the bottom of said shell to said still.

In testimony whereof, I have hereunto set my hand at the city and county of San Francisco, California, this 18th day of October, 1921.

DANIEL PYZEL.
